UNITED STATES PATENT OFFICE

ALBERT E. PAGE, OF BROOKLYN, NEW YORK, ASSIGNOR TO SCOTT AND WILLIAMS, INCORPORATED, OF NEW YORK, N. Y., A CORPORATION OF MASSACHUSETTS

TRANSFER MECHANISM FOR CIRCULAR KNITTING MACHINES

Application filed May 8, 1929. Serial No. 361,418.

This invention relates to mechanism for transferring a circular knitted web to the needles of a knitting machine, and more particularly to that type of transferring mechanism in which the loops of the fabric are transferred from the quills of a transfer ring onto the needles of a knitting machine, as for example, in putting the ribbed top of a half hose onto a plain knitting machine preparatory to the knitting of the leg and foot of the half hose. This purpose of the invention is to coordinate properly the transferring operations with the knitting operations of the machine, to make them automatic and to provide simplified and accurate mechanism.

According to my invention the transfer ring is permanently attached in a revoluble manner and the operation of "topping", i. e. running the stitches onto the quills of the point ring is performed without removal of the ring from the machine. The ring is mounted on a pivot carrier arm as heretofore known but the mechanism for controlling the swinging of the carrier arm is independent of all the knitting operations of the machine and yet is so controlled that the operation of transfer can be accomplished only when the machine is ready for it.

Mechanism of this type and for this general purpose is described and claimed broadly in the L. N. D. Williams application Serial No. 355,765 filed April 17th, 1929. My present invention is an improvement on the mechanism shown in that application.

In the drawings Fig. 1 is a perspective view of the new transfer mechanism partially inverted over the needle cylinder of the well-known Scott and Williams type of seamless hosiery machine.

Fig. 2 is a side elevation of the transfer ring and carrier arm in inverted position.

Fig. 3 is a side elevation of the mechanism for locking the needle cylinder in registry with the quills of the point ring.

Fig. 4 is an elevation of the transfer ring and locking mechanism showing the transfer ring locked in idle or retracted position,

Fig. 5 is a plan view of the locking mechanism of Fig. 4.

Fig. 6 is a detail partly in section of the locking mechanism.

Fig. 7 is a perspective view of the carrier arm bracket and latch. 55

Fig. 8 is an elevation of the transfer ring in inverted position.

Fig. 9 is a vertical section through the transfer ring taken on the line 9-9 of Fig. 60 10.

Fig. 10 is a plan view of the top of the transfer ring when inverted showing the means of centering same.

Fig. 11 is a horizontal sectional view 65 through the transfer ring taken on line 11-11 of Fig. 9.

Fig. 13 is a horizontal section through the transfer ring taken on line 13-13 of Fig. 12.

While Fig. 14 is a vertical elevation of the transfer ring partly in section taken on the line 14-14 of Fig. 11. 75

The invention is shown embodied in the usual Scott and Williams type of seamless hosiery knitting machine having a revoluble needle cylinder 260 carried in a bedplate B with an outside sinker cam cap 300 and 80 latch ring arm 550 for carrying the yarn fingers. The yarn fingers are controlled as usual from the main pattern drum 120 by means of the thrust rods 460.

The transfer mechanism comprises a transfer ring carried by an arm 16 pivoted to swing about an axis 15 on a bracket 14 carried on the bedplate B of the machine. The mechanism for coordinating the movements of the carrier arm with other operations of the machine includes locking mechanism independently controlled from the main pattern drum 120 by means of a cam 501 thereon actuating a thrust rod 460a. This mechanism is adapted automatically to cause 85 locking of the needle cylinder with its needles in registry with quills q of the point ring and automatically to unlock the needle cylinder when the transfer ring is retracted after completion of the transfer operation. 95 100

It also holds that transfer ring in retracted position until the knitting machine has knitted another stocking, stopped revolving and locked the needle cylinder with its needles in a position which will register with the quills of the transfer ring when inverted over the needle cylinder. The mechanism which accomplishes these objects will now be described.

10 The upper end of a thrust rod 460a is pivotally connected to the rear end of an operating lever 42 which lever is pivoted on the carrier arm bracket 14. Attached to this same end of the operating lever 42 is a tension spring 52 whose lower end is fastened to a fixed part of the machine in order that the spring may tend to keep the thrust rod down in contact with the surface of the main pattern drum. The forward end of this operating lever 42 is formed as shown in Figs. 1 and 5, and extends under the axis 15 of the carrier arm 16. It also has an ear, or lug 159, extending laterally, pierced to permit free passage of a locking pin 36. This locking pin passes through an opening in a stationary cover of the bedplate B and into a hole 51 in a horizontal bevel gear or ring 37. It might be mentioned at this point that the lower end of the locking pin 36 is preferably tapered slightly in order to assist in bringing the needle cylinder into accurate registry. The bevel gear 37 is fast on the needle cylinder and revolves the latter. It will, therefore, be obvious that when the locking pin 36 is pushed down through the bedplate into the hole 51 in the bevel gear 37 the needle cylinder is locked against rotation. The hole in the cover of the bedplate and the hole 51 in the bevel gear are so located that when they are in registry the needles n of the needle cylinder 260 are in a position where each will be in registry with and adapted to slide into a hollow quill in the transfer ring when the latter is inverted over the needle cylinder. The locking pin 36 is given a lost motion connection with its operating lever 42 by means of a cotter pin passing through the locking pin just above the ear or lug 159 on the operating lever and a compression spring 158 on the locking pin below that ear 159 and a shoulder 160 on the pin supporting the lower end of the compression spring.

55 In order that the machine may knit after the transfer operation is completed it is necessary that the locking pin 36 be withdrawn from operative position and this cannot be done from the main pattern drum without racking same. The drum cannot be racked except by rotating the needle cylinder and that is impossible without withdrawing the pin. In accordance with my invention, I therefore provide means in which the cam 501 moves from under the

foot of the thrust rod 460a before the locking pin 36 drops home, and maintains the spring pressure downward on that pin before transfer and causes its withdrawal from the horizontal bevel gear 37 after transfer by independent means controlled by the transfer mechanism. These means are provided to hold the compression spring 158 in operative position even when the ear 159 of the locking lever 42 is freed to rise under the influence of the tension spring 52 by the thrust rod 460a riding off the cam 501. These independent means are adapted to hold the spring in operative position after it has once been compressed by the locking lever 42 until the transfer arm 16 has been inverted over the needle cylinder and retracted again. Pivoted connected to the end of the locking lever 42 is a vertical safety pin 40 moving through an arm 41 of the transfer bracket 14. The upper end of this safety pin is in line with a circular cam 39 located about the axis 15 and the carrier arm 16 and revolving with the carrier arm. The major portion of this carrier arm cam is preferably of such a height that when it is in engagement with the safety pin 40 that pin will serve to hold the ear 159 of the locking lever 42 down to a level which keeps the spring 158 under compression. In other words as long as the cam 39 on the carrier arm is in engagement with the safety pin 40 the locking pin 36 will be spring-pressed downward and will drop into the hole 51 in the bevel gear 37 as soon as that hole comes into register with the pin. The location of the cam 39 about the axis 15 is such that the normal height of the cam extends far enough around to be in contact with the safety pin from the fully inverted position of the transfer ring to just short of the fully retracted position. At the end of the cam 39 corresponding to the retracted position of the transfer ring, there is a low surface 166 and adjacent to the end of that surface, but slightly higher, is a spring-pressed locking plunger whose end is adapted to meet the safety pin 40 as that pin rides along the surface 166 above mentioned. This locking plunger 163 is held forward in contact with the end of the low surface 166 by a spring 164 confined in the transfer arm 16 by a screw 165.

The operation of the device as the transfer ring is retracted can be observed in Figure 6. As the carrier arm 16 is retracted the safety pin 40 under the influence of the spring 52, acting through the locking lever 42, maintains contact with the low surface 166 and coming into engagement with the spring-pressed locking plunger 163 pushes that plunger back into the carrier arm 16 against the tension spring 164. As soon as the safety pin 40 has pushed the locking plunger 163 far enough to itself clear the

end of the low surface 166, the spring 52 forces the safety pin 40 into the notch 166a between the end of the low surface 166 and the main portion of the carrier arm 16. 5 When the pin 40 is thus located in the notch 166a it will be obvious that the carrier arm 16 cannot be inverted over the needle cylinder again and that therefore the transfer ring cannot be inverted unless and until released by the selecting mechanism controlling the knitting operations, i. e. the main pattern drum 120.

When the thrust rod 460a rides up onto the came 501 on the main pattern drum, the locking lever 42 pulls the safety pin 40 down out of the notch 166a at the end of the low level 166 of the cam 39, and the notch 166a is promptly filled automatically by the locking plunger 163. When the thrust rod 460a rides off the cam 501 the tension spring 52, acting through the locking lever 42, pushes the safety pin 40 upwardly into contact with the locking plunger 163, but the safety pin 40 cannot rise far enough to allow the ear 159 of the locking lever 42 to release the compression spring 158. The locking pin 36 therefore remains under spring pressure until the hole 51 in the level gear is brought into register with it, and even after it has 30 dropped into operative position the safety pin 40 holds the locking lever 42 down, as shown for instance in Fig. 3.

It will be obvious that from the moment the thrust rod 460a rode up on the cam 501 35 on the main pattern drum the carrier arm 16 was unlocked as far as concerns the safety pin 40, and could be inverted over the needle cylinder. However, the locking pin 36 had not at that time dropped into locking position with the horizontal bevel gear and the needle cylinder was, therefore, not in register with the prospective position of the quills of the transfer ring. Therefore it is preferable to have an additional locking 45 means to hold the carrier arm retracted after the locking pin has been put under spring pressure until the locking pin actually drops home into the hole 51 in the bevel gear. For this purpose I provide a locking 50 catch 161, pivotally mounted on the bracket 14. One end of this catch overlies the upper end of the locking pin 36 and the other end is made in the form of a hook adapted to overlie a pin 167 projecting laterally from 55 the carrier arm 16. This locking catch is of such shape that when its locking pin end is in contact with the upper end of the locking pin 36 the hook end will be in engaging 60 position with the pin 167 until the locking pin 36 drops home into operative position. When the locking pin 36 drops down to this 65 position a tension spring 162 fastened between the arm 41 of the bracket 14 and the locking catch 161 pulls the hook out of en-

gagement with the pin 167, freeing the carrier arm 16 for inversion over the needles.

The novel means of mounting the transfer ring on the carrier arm 16 in cooperative relation to the parts previously described will now be set forth. This mechanism is claimed in my divisional application Ser. No. 433,378 filed March 5, 1930.

As shown in the drawings the carrier arm 16 is of such a shape that when retracted the transfer ring is in a horizontal plane with the quills *q* pointed upwardly and with the transfer ring held revolubly in a manner which will be described in the subsequent paragraph. The carrier arm 16 can, if desired, be made of two parts, the lower arm 16 and an upper arm 168 with set screws joining the two arms adapted to provide vertical adjustment of the transfer ring relatively to the needle cylinder. The upper arm 168 has four arms thereon to which the transfer ring is attached in the following manner. There is a mounting plate or pilot 169 screwed to the various legs of the upper transfer ring arm 168, the exact central position of this pilot being adjustable by means of four horizontal chucking screws 181 passing through the central portion of the arm 168 into engagement with a short central collar 169a of the pilot. This construction is shown in Figs. 2, 8, 9 and 10. It will be observed that there is a vertical pilot sleeve 170 forming a unitary part of the pilot and stretching outwardly toward the quills of the transfer ring in the form of a complete cylinder (Fig. 13). This pilot sleeve provides a firm well centered mounting for the transfer ring proper and the other parts about to be described. Fitting loosely around the outside of this pilot sleeve 170 is a stripper ring 175 carrying the individual strippers 176 located between the individual quills *q* and adapted to strip the terminal stitches and push them onto the needles of the knitting machine. The transfer ring proper in the construction shown in the drawings is composed of a transfer ring base 171 slidably mounted outside the stripper ring 175, an inside transfer ring 174 on top of the base 171 and an outside transfer ring 173 threaded onto the upper end of the base and holding the inside transfer ring and quills assembled in position. The upper ends of the strippers overlie the top of the inside transfer ring in order that they may be intercalated between the quills *q*. The vertical movement of the base 171 is limited by an external shoulder 171a on the base and two adjustable transfer ring stops 172 adapted to engage the shoulder 171a. When the transfer ring is inverted over the needle cylinder and the transfer ring is pushed down toward the needles these stops, catching on the ledge or shoulder 171a, accurately define the degree of inter-engage- 130

ment of the needles with the quills. This engagement can be adjusted by means of vertical screws lying on the under surface of the pilot 169, the adjustment being locked 5 by means of the screws which mount the stops on the pilot. In order that the stripper ring and strippers may have their movement relatively to the transfer ring limited to the proper extent, a small vertical slot is 10 cut in the transfer ring base and a screw 177 carried by the stripper ring located in that slot. The ends of the slot serve to determine the limits of movement of the strippers relatively to the transfer ring.

15 For the purpose of actuating the transfer ring and the strippers an axial handle 24 is provided which passes through the sleeve 169a of the pilot. An operating button 25 is provided on the end of this handle and a 20 light spring 26 is preferably located between this button 25 and the sleeve 169a. On the inner end of this operating handle 24 two stripper operating fingers 178 are adjustably fastened by means of two screws 25 179 passing through slots 179a in the fingers, these fingers being laid side by side on the end of the handle 24 and projecting in opposite directions from the axis of the handle through openings 30 180 in the pilot sleeve 170. The ends of these operating fingers project into a circumferential groove in the stripper ring and the strippers therefore move in unison with the handle 24. The openings 180 in the 35 vertical pilot sleeve are high enough to permit advancement of the strippers to the necessary limit as defined by the stop pin 177 even when the transfer ring is farthest away from the pilot 169 with the quills *q* in engagement with the needles *n* of the needle cylinder.

The transfer ring base 171 when resting on the top surface of the pilot 169 is prevented from rotating relatively to the pilot 40 by means of keys and complemental keyways. In the drawings there are two keys 182 on the pilot projecting upwardly into keyways 183 on the lower edge of the transfer ring base 171. These keys fit into the keyways 183 without any lost motion and in this way the transfer ring is kept accurately in register with the needles. If it is desired to rotate the ring while the same is in retracted position in order to assist the operation of topping, i. e. putting the stitches of the ribbed top on the quills of the transfer ring, the transfer ring can be lifted away from the pilot as far as permitted by the ring stops 172. In this position the transfer 45 ring base is above the tops of the keyways 182 and it is therefore possible to rotate the transfer ring. When two keyways are employed as shown in the drawings, it is preferable to make the keys dissimilar in order 50 that the transfer ring may not drop down

into register with the keys when half a revolution has been completed. In the drawings these keys and their complemental keyways are made dissimilar with regard to the axis of the transfer ring by locating them in circumferentially unequal positions. It will be obvious that when the transfer ring is rotated the complemental keyways will not both be in register with the keys at the same time when the transfer ring has been turned 70 about one-half of a revolution, but of course when the ring has been turned 360° the keys and keyways will match up simultaneously and the transfer ring will drop down onto the pilot in proper registry again. By having two keys and keyways the transfer ring is better supported and does not jam.

The construction of the machine having been described, its operation will now be set forth. Assuming that the machine has finished knitting the previous stocking, including the loopers rounds, a lug on the pattern chain causes a rack of the main pattern drum which raises the active yarn finger to inactive position, cutting and clamping the 80 yarn and at the same time causes the completed stocking to be pressed off the needles. The main pattern drum is then given a second rack which raises the latch ring out of operative position and shifts the driving 85 belt to the idle pulley, thus stopping the machine. This shifting of the belt occurs at such a moment that the machine stops at about one-quarter of a revolution before the 90 hole 51 in the bevel gear 37 comes into register with the locking pin 36. This same rack 95 also brings the cam 501 under the foot of the locking lever thrust bar 460a, causing the compression spring 158 to put the locking pin 36 under pressure toward operative 100 position with the lower end of the locking pin riding on the surface of the horizontal bevel gear 37.

The tipping of the locking lever 42 which compresses the spring 158, also pulls down 110 the safety pin 40 out of the notch 166a and the spring 164 thereupon snaps the locking plunger 163 across the notch 166a, preventing the safety pin from returning into the notch and holding it down far enough to 115 keep the locking pin 36 under pressure from the spring 158.

Just as the rack which brought the cam 501 under the thrust rod 460a is completed, the cam 501 comes from under the thrust 120 rod and the spring 52 attempts to pivot the locking lever 42 to release the locking pin. It cannot do this, however, because the locking plunger 163 lies across the top of the safety pin 40 and the locking pin 36 125 therefore stays under spring-pressed pressure downward and the thrust rod 460a remains suspended a short distance above the surface of the main pattern drum. This locking out of the safety pin 40 to continue 130

the spring pressure on the locking pin 36 is one of the novel features of the invention.

The driving belt now being on an idle pulley and the racking of the machine having stopped, the operator turns the machine by hand about one-quarter of a revolution until the locking pin 36 drops into the hole 51 in the horizontal bevel gear 37. It will be obvious that, if desired, the completion 10 of the second rack may be delayed until it occurs simultaneously with the making of the one-quarter revolution of the needle cylinder in which case the thrust rod 460a can be made to ride off the cam 501 about 15 the same time that the locking pin 36 drops home into the hole in the bevel gear, but I have found it convenient to complete the racking of the main pattern drum 120 automatically before the operator makes the one-quarter turn by hand.

The operator having made the one-quarter turn and the pin having dropped into locking or operative position the apparatus is in the position shown in Fig. 3.

Up to this time the transfer ring has been in the retracted position shown in Fig. 4 with the locking catch 161 hooked over the pin 167. The locking catch has been held in this position against the tension of its 25 spring 162 by the engagement of the back end of the locking catch with the top of the locking pin 36. As soon as the locking pin drops down into operative position, however, the spring 162 pivots the locking 30 catch and releases its hold on pin 167. The safety pin 40 having previously been withdrawn from the notch 166a, the operator can now invert the transfer ring as shown in Fig. 1 until it assumes the position

40 shown in Fig. 2. The transfer ring plunger spring 26 prevents the strippers 176 from being inadvertently moved relatively to the quills *q* but the weight of the transfer ring causes the ring to drop down to the position shown in Figs. 2 and 8, keeping the strippers 176 in contact with the outer surface of the inside transfer ring. The quills are now in engagement with the needles *n*, as shown in Fig. 2, and the operator by pressing downwardly on the handle 45 25 can advance the strippers and transfer the terminal loops of the ribbed top to needles of the knitting machine. While this is happening the locking pin 36 is held 50 against accidental withdrawal from active position by the cam 39 and the safety pin 40.

The operator still holding the handle 25 again swings the transfer ring through an arc returning it to the retracted position 60 shown in Fig. 4. As the carrier arm approaches this retracted position the safety pin 40, following the surface of the cam 39 closely by virtue of the tension spring 52

on the locking lever 42, rides down on the low surface 166 and engages against the end of the locking plunger 163 as shown in Fig. 6. The completion of the retraction of the carrier arm pushes the plunger 163 back out of the notch 166a and the spring 52 raises the locking pin out of operative position and snaps the safety pin 40 into the notch 166a. Thus this movement simultaneously releases the bevel gear for further revolution and locks the transfer ring against inversion over the needle cylinder until the pattern drum has once more completed its full knitting cycle and brought cam 501 under the foot of the thrust rod 460a.

The claims of this application have more particular reference to mechanism stressing resilient means acting on a device for locking the needle cylinder against rotation, and simultaneously with the locking of the cylinder, releasing the transfer arm for inversion over the needle cylinder.

Other features shown and described in this application are claimed in the copending applications of L. N. D. Williams, No. 381,791 and A. E. Page, Serial No. 433,378 (a division of the present application).

What I claim is:—

1. A circular knitting machine having a revoluble needle cylinder, stitch transfer mechanism adapted to be moved into and out of operative relation with the cylinder, and a pin to lock the cylinder against rotation, in combination with a spring to press said pin into locking position, a lever to put said spring into operative position and means adapted to hold said spring in said position.

2. A circular knitting machine having a revoluble needle cylinder, stitch transfer mechanism adapted to be moved into and out of operative relation with the cylinder, and a pin to lock the cylinder against rotation, in combination with a spring to press said pin into locking position, a lever to put said spring into operative position and a plurality of independently actuated means acting on said lever to hold said spring in said position.

3. A circular knitting machine having a revoluble needle cylinder, stitch transfer mechanism adapted to be moved into and out of operative relation with the cylinder, and a pin to lock the cylinder against rotation, in combination with a spring to press said pin into locking position, a lever to put said spring into operative position and means controlled by said transfer mechanism adapted to hold said spring in said position.

4. A circular knitting machine having a revoluble needle cylinder, stitch transfer mechanism adapted to be moved into and out of operative relation with the cylinder, and a pin to lock the cylinder against rotation.

tion, in combination with a spring to press said pin into locking position, a lever to put said spring into operative position and means controlled by said transfer mechanism adapted to hold said spring in said position until said transfer mechanism has been moved into and out of operative relation with the cylinder.

5. A circular knitting machine having a
10 revoluble needle cylinder, stitch transfer
mechanism adapted to be moved into and
out of operative relation with the cylinder,
a pin adapted to lock the cylinder against
15 rotation, and a safety pin adapted to lock
said transfer mechanism out of operative
relation, in combination with a spring adapt-
ed to press said cylinder locking pin into
cylinder-locking position, and a lever adapt-
20 ed to put said spring into operative position
and simultaneously remove said safety pin
from locking position.

6. A circular knitting machine having a
revoluble needle cylinder, stitch transfer
mechanism adapted to be swung into and
25 out of operative relation with said cylinder,
a safety pin to lock said transfer mechanism
out of operative relation, a pin adapted to
lock said cylinder against rotation, and a
30 spring adapted to press said cylinder-lock-
ing pin into operative position, in combina-
tion with a lever adapted to put said spring
into operative position and simultaneously
35 remove the safety pin from locking position,
and a plunger adapted to prevent the return
of said safety pin to locking position.

7. A circular knitting machine having a
revoluble needle cylinder, stitch transfer
mechanism adapted to be swung into and
40 out of operative relation with the cylinder,
a safety pin adapted to lock said transfer
mechanism in retracted position and a
spring-pressed plunger adapted to prevent
45 movement of said safety pin to locking position
until said transfer mechanism has been
inverted over the needle cylinder.

8. A circular knitting machine having a
revoluble needle cylinder, stitch transfer
mechanism adapted to be swung into and
50 out of operative relation with the needle
cylinder, a safety pin adapted to lock said
transfer mechanism against inversion over
the cylinder, a lever controlling said safety
55 pin, a pattern drum controlling said lever
and a spring tending to cause said lever to
move said pin to locking position in com-
bination with a spring-pressed plunger
adapted to prevent movement of said safety
60 pin to locking position until said transfer
mechanism has been inverted over said
cylinder.

9. A circular knitting machine having a
revoluble needle cylinder, stitch transfer
mechanism adapted to be swung into and
65 out of operative relation with said needle

cylinder, a pin to lock said cylinder against
rotation, a spring to press said pin into
locking position, and a safety pin adapted
70 to lock said transfer mechanism in retracted
position, said safety pin being associated
with said spring and adapted, when out of
locking position, to cause said spring to re-
main in operative position, in combination
75 with a plunger adapted to hold said safety
pin out of locking position until said trans-
fer mechanism has been inverted over said
cylinder and a cam surface adapted to hold
said spring and locking pin in cylinder
80 locking position during the operation of in-
verting and retracting said transfer mech-
anism.

10. A circular knitting machine having a
revoluble needle cylinder and a pattern
drum, stitch transfer mechanism adapted to
be moved into and out of operative relation
85 with said cylinder, a pin to lock said cylinder
against rotation and a compression spring
on said pin adapted, when compressed, to
press said pin into locking position, a
90 safety pin adapted to lock said transfer
mechanism in retracted position, in combi-
nation with a spring-pressed plunger adapt-
ed to hold said safety pin out of locking
95 position until the transfer mechanism has
been inverted and retracted, a cam adapted
to hold said spring and locking pin in
cylinder locking position during the invert-
ing and retracting operation, but permitting
100 said safety pin to push said plunger aside
and gain access to its locking position upon
completion of the retracting movement, a
lever controlled by the pattern drum
adapted to compress said locking pin spring
105 and simultaneously withdraw said safety
pin from locking position, and a spring
tending to push said safety pin toward lock-
ing position.

11. A circular knitting machine having
a revoluble needle cylinder, stitch transfer
mechanism adapted to be swung into and
110 out of operative relation with the needle
cylinder, a pin adapted to lock said needle
cylinder against rotation and a catch
adapted to lock said transfer mechanism in
115 inoperative position until said locking pin
is in locking position.

12. A circular knitting machine having a
revoluble needle cylinder and a pattern
drum, stitch transfer mechanism adapted to
be moved into and out of operative relation
120 with the cylinder, a safety pin to lock said
mechanism in retracted position and a pin
to lock the cylinder against rotation, in com-
bination with means operated in one direc-
125 tion by the pattern drum to press said
cylinder locking pin toward locking posi-
tion and release said transfer mechanism for
inversion over the cylinder, and operated
130 in the other direction by inversion and re-

traction of the transfer mechanism to lock said transfer mechanism in retracted position and remove said cylinder locking pin, substantially as shown and described.

5 In testimony whereof I have signed my name to this specification.
